(57) **CLAIM**

The ornamental design for a security device, as shown and described.

DESCRIPTION

FIG. 1 is a front view of a security device according to the present design.

FIG. 2 is a back view of the security device of FIG. 1.

FIG. 3 is a left side view of the security device of FIG. 1.

FIG. 4 is a right side view of the security device of FIG. 1.

FIG. 5 is a top view of the security device of FIG. 1.

FIG. 6 is a bottom view of the security device of FIG. 1; and, FIG. 7 is a front perspective view of the security device of FIG. 1.

The broken lines are directed to unclaimed features of the security device and form no part of the claimed design.

1 Claim, 5 Drawing Sheets

FIG. 1

FIG. 2

FIG. 3

FIG. 4

FIG. 5

FIG. 6

FIG. 7
